CLAIM

The ornamental design for a crowned decking board, as shown and described.

DESCRIPTION

FIG. 1 is a perspective view of a crowned decking board in accordance with the present design with the board shown in broken lines indicating an indeterminate length.

FIG. 2 is a front view thereof, with the rear view being the same.

FIG. 3 is a right side elevation view thereof, with the left side being the same.

FIG. 4 is a top plan view thereof; and,

FIG. 5 is a bottom plan view thereof.
